Specification for Design.

Patented Sept. 26, 1916.

Application filed August 11, 1915. Serial No. 45,066. Term of patent 14 years.

To all whom it may concern:

Be it known that I, CHAUNCEY W. ABBOTT, a citizen of the United States, residing at Pittsburgh, in the county of Allegheny and State of Pennsylvania, have invented a new, original, and ornamental Design for Covers for Corner-Boxes for Electrical Conduits, of which the following is a specification, reference being had to the accompanying drawing, forming part thereof.

In the drawings, Figure 1 is a face view;

Fig. 2 is a side view; and Fig. 3 is an end view, of a cover for corner boxes for electrical conduits, showing my new design.

I claim:

The ornamental design for a cover for corner boxes for electrical conduits, as shown.

CHAUNCEY W. ABBOTT.
